JOHN V. ABRONSKI, OF PITMAN, NEW JERSEY

SCREEN

Application filed June 13, 1929. Serial No. 370,487.

The present invention relates to screens and particularly to the construction of frames therefor.

An object of the invention is to provide an improved screen frame construction.

A further object is to provide a screen frame with which the wire mesh may be simply and quickly connected; and which will provide an assembly positive against dis-

lodgment of one element from the others.

A still further object is to provide in a screen of this character improved interfitting clamping parts for the screen material which may be readily disengaged one from the other for wiring or rewiring the same.

A further object is to provide a screen frame, the improved construction of which is such as to lend itself to the ready manufacture of the members thereof by extrusion or rolled metal process.

A still further object is to provide improved frame members all the parts whereof are formed integrally of a homogeneous metal construction.

Further objects are to provide an improved insect-proof construction in screen frames with frames of interfitting parts which will be neat in appearance and which may be easily adapted to sliding or stationary fit within a window frame and which may be adapted to various deformities of a window frame.

A still further object is to prolong the life of the screen and to protect the screen at points of greatest wear.

A screen made in accordance with the principles of the invention comprises frame members having an interfitting relation to each other for clamping the screen material therebetween; which frame members consist of grooved frame members proper and improved splines nesting in said grooves.

The disengagement of the splines from the grooves may be facilitated by providing lips extending from one side thereof affording members under which a tool may be inserted for a prying action thereagainst.

The splines and frame members proper may be further provided with means for locking the edges of the screen material in

the grooves in the nature of interengaging keys and keyways and the lips which may be in the nature of continuous flanges along one edge extending over the frame members on the sides of the grooves over which the screen material extends may be employed to enhance the neatness of appearance of the connection between the screen cloth and frame.

This appearance may be further enhanced by insetting this side the depth of the screen and lip so as to present the surface of the spline and the associated frame member in the same plane.

Tenacity of grip between the frame members and splines may be increased by forming the grooves slightly undercut and the splines of complementary cross-section; this construction also cooperating with the interengaging keys and keyways to this end.

The improvement in the construction whereby the frames adapt themselves to extrusion manufacture is the extension of all parts of the members thereof in right lines longitudinally of the frame members.

The frames may be made up of combinations of frame members all of which are of the same construction, or may be made of various combinations of the frame members hereinafter described and illustrated in the accompanying drawings.

An embodiment of the invention conforming to the principles laid down in the foregoing paragraphs is illustrated in the accompanying drawings, in which:

Figure 1 shows a window fragmentarily in the frame of which is mounted a screen made in accordance with the present invention.

Figure 2 is a section on the line 2-2 of Figure 1, showing the connection between the screen wire and the screen frame and also a sliding connection of the screen frame with the window frame; this figure being on an enlarged scale compared with Figure 1.

Figure 3 is a detail view on an enlarged scale compared to Figure 2 and showing one form of frame member and interengaging spline, the said frame member being associated with a slideway for connection with

the window frame and having a compensating flange extending into the slideway,

Figure 4 shows the invention in a somewhat different aspect and showing a compensating fitting or attaching flange on the edge of the screen frame and a modified form of interengaging key and keyway,

Figure 5 is a fragmentary view showing a slideway in perspective, and

Figure 6 is a view similar to Figure 3 with the compensating strip omitted.

Referring to the drawings in detail, 10 designates the window frame in which the slideways 11 are mounted, 12 designates the screen which is comprised of meshed screen material 13 and side frame members 14 and top and bottom frame members 14^a. These side frame members may be formed of any suitable material as metal, either extruded, 20 rolled or otherwise produced.

The screen material 13 may be connected to the frame by suitably anchoring the edges thereof in grooves 15 formed in one face of the frame members proper as designated by 25 the numeral 16. These grooves are preferably slightly constricted or undercut as at 17, the undercut portion of which may be more or less curved or circular in contour, the outlet of the grooves being between substantially straight parallel walls 18 and 19.

An interengaging connection between the spline and the frame member proper is provided and a further engagement is provided in the nature of interengaging keys 20 and 30 keyways 21, in the present showing the keys being formed in the bottom of the grooves and the keyways in the bottom of the spline. These engaging keys and keyways are preferably angular in cross-section in order to 40 form a biting grip of the screen material between the interengaging frame members and the spline.

The frame members are provided with shoulders 22 and 23 on either side of the 45 grooves, the shoulders one, as the shoulder 23 being depressed compared with the spaced shoulder sufficiently to accommodate the screen material and overhanging lips 24 formed on one edge of the splines.

By this construction both the frame member proper and the spline present their outer surfaces in a single plane, the lip 24 serving not only to improve the appearance of the 55 screen but also affording an effective protection to the screen material along the line of maximum wear. These lips, which are in the nature of extended flanges, also provide additional clamping means for holding the screen material in place. These lips may be omitted where desired.

An important function of this lip member is to provide a surface against which a tool inserted between the same and the screen 65 material for dislodging the spline may oper-

ate should it be desired to renew the wire covering the frame.

The outer edges of certain of the frame members may be provided with compensating flanges, as shown at 25 in Figure 3 of the 70 drawings or at 25^a in Figure 4. This compensating flange may be used as a slide riding in a suitable slideway 26 which may consist of flanges spaced apart a sufficient distance to accommodate the compensating 75 flange 25. This compensating flange when designed to be used as a slide may be inset the thickness of the outermost flange constituting the slideway so as to give a continuity of surface between the frame member and the 80 slideway. This slideway may also be provided with an attaching flange 27 adapted for use in attaching the same to the window frame. This flange may be provided with a plurality of apertures such as indicated at 85 28 in Figure 5 of the drawings.

The compensating flange when used for attaching the screen in a non-sliding manner to a window frame may when elected provide the compensating flange as at 25^a in Figure 4 in a plane with the surface 22 of the frame member with which it is associated and suitable apertures provided in this flange for attaching hinges, latches or other accessories for attaching the same to the window frame so that the frame may be readily attached and detached, or swung outwardly from the window frame.

The spline may be either of solid formation, as in Figure 3, or it may be hollow, as 90 in Figure 4. The construction shown in Figure 6 is particularly adapted for top and bottom frame members, although it may also be used as side frame members under certain circumstances and where the frame is to be used in a stationary position within the window frame, one or more, or even all of the frame members may be provided with flanges such as is shown at 25 or 25^a respectively, in 95 Figure 4.

The above description, together with the illustrations, are to be considered as merely 100 illustrative of the invention and it is to be clearly understood that various changes in details of construction may be made in the manufacture of the invention within the scope of the invention as hereinbefore set forth and hereinafter claimed.

I claim:—

1. A screen frame comprising top and side frame members, said side frame members having flanges extending laterally therefrom adapted to be trimmed to fitted size.
2. A screen frame comprising top and side frame members, said side frame members having flanges extending laterally therefrom and slideways for said flanges comprising a pair of flanges spaced apart substantially the thickness of the first named flanges said first named flanges adapted to be trimmed to re- 115

duce the overall size of the screen to fit between the opposed slideways.

3. In a screen unit a frame member having a groove therein, constricted at the opening, one side of the opening being depressed below the ultimate plane and a fastening member proportioned to be forced through said constriction and having a lip accommodated wholly within the depression.

10 4. In a screen unit a frame member having a curvilinear groove therein constricted at the opening, one side of the opening being depressed below the ultimate plane, and a fastening member proportioned to be forced through said constriction and having a lip accommodated wholly within the depression.

15 5. In a screen unit a frame member having a groove therein constricted at the opening, one side of the opening being depressed below the ultimate plane, and a fastening member wider than the opening proportioned to be forced through said constriction and having a lip accommodated wholly within the depression.

20 6. In a screen unit a frame member having a curvilinear groove therein constricted at the opening, one side of the opening being depressed below the ultimate plane, and a fastening member wider than the opening proportioned to be forced through said constriction and having a lip accommodated wholly within the depression.

25 7. In a screen unit a frame member having a groove therein constricted at the opening, one side of the opening being depressed below the ultimate plane, and a fastening member proportioned to be forced through said constriction together with a screen fabric and having a lip accommodated wholly within the depression.

40 8. In a screen unit a frame member having a curvilinear groove therein constricted at the opening, one side of the opening being depressed below the ultimate plane, and a fastening member proportioned to be forced through said constriction together with a screen fabric and having a lip accommodated wholly within the depression.

50 9. In a screen unit a frame member having a groove therein constricted at the opening, one side of the opening being depressed below the ultimate plane, and a fastening member wider than the opening proportioned to be forced through the said constriction together with a screen fabric, the walls of the groove yielding therefor, and having a lip accommodated wholly within the depression.

55 10. In a screen unit a frame member having a curvilinear groove therein constricted at the opening, one side of the opening being depressed below the ultimate plane, and a fastening member wider than the opening proportioned to be forced through the said constriction together with a screen fabric, the walls of the groove yielding therefor, and

having a lip accommodated wholly within the depression.

11. In a screen unit a frame member having a groove therein, constricted at the opening and with a rib opposite, one side of the opening being depressed below the ultimate plane, and a fastening member proportioned to be forced through said constriction and having a groove complementary to the rib and having a lip accommodated wholly within the depression.

15 12. In a screen unit a frame member having a curvilinear groove therein constricted at the opening and with a rib opposite, one side of the opening being depressed below the ultimate plane, and a fastening member proportioned to be forced through said constriction and having a groove complementary to the rib and having a lip accommodated wholly within the depression.

20 13. In a screen unit a frame member having a groove therein constricted at the opening and with a rib opposite, one side of the opening being depressed below the ultimate plane, and a fastening member wider than the opening proportioned to be forced through said constriction and having a groove complementary to the rib and having a lip accommodated wholly within the depression.

25 14. In a screen unit a frame member having a curvilinear groove therein constricted at the opening and with a rib opposite, one side of the opening being depressed below the ultimate plane, and a fastening member wider than the opening proportioned to be forced through said constriction and having a groove complementary to the rib and having a lip accommodated wholly within the depression.

30 15. In a screen unit a frame member having a groove therein constricted at the opening and with a rib opposite, one side of the opening being depressed below the ultimate plane, and a fastening member proportioned to be forced through said constriction together with a screen fabric and having a groove complementary to the rib and having a lip accommodated wholly within the depression.

35 16. In a screen unit a frame member having a curvilinear groove therein constricted at the opening and with a rib opposite, one side of the opening being depressed below the ultimate plane, and a fastening member proportioned to be forced through said constriction together with a screen fabric and having a groove complementary to the rib and having a lip accommodated wholly within the depression.

40 17. In a screen unit a frame member having a groove therein constricted at the opening and with a rib opposite, one side of the opening being depressed below the ultimate plane, and a fastening member wider than the opening proportioned to be forced through the said constriction together with a screen fabric, the walls of the groove yielding there-

for and having a groove complementary to the rib and having a lip accommodated wholly within the depression.

18. In a screen unit a frame member having a curvilinear groove therein constricted at the opening and with a rib opposite, one side of the opening being depressed below the ultimate plane, and a fastening member wider than the opening proportioned to be forced through the said constriction together with a screen fabric, the walls of the groove yielding therefor and having a groove complementary to the rib and having a lip accommodated wholly within the depression.

19. In testimony whereof I have signed my name to this specification.

JOHN V. ABRONSKI.
